UNITED STATES PATENT OFFICE.

JOHN SCHUTZ, OF CHICAGO, ILLINOIS, ASSIGNOR TO HERMAN H. NEWBERGER, OF CHICAGO, ILLINOIS.

AUTOMATIC STOP MECHANISM.

Application filed July 5, 1919. Serial No. 308,877.

To all whom it may concern:

Be it known that I, JOHN SCHUTZ, a citizen of the United States, residing at Chicago, in the county of Cook and State of Illinois, have invented certain new and useful Improvements in Automatic Stop Mechanism, of which the following is a specification.

My invention relates to improvements in automatic stop mechanisms for safe-guarding knitted or woven fabrics.

It is generally well known that when moving threads or yarns, that are to constitute knitted or woven fabrics, are accidentally broken, in the course of the knitting or weaving operation, or when a knot in the thread or yarn is about to pass into the machine, of which the fabric is made, such contingencies, if allowed to pass unnoticed, will cause the resultant fabric to be defective and not of prime value.

When a large number of such fabricating machines are under the supervision of a single attendant, and a correspondingly large number of threads or yarns are associated with the machines, it is practically impossible to visually detect the aforesaid defects in time to prevent the resultant damage to the fabricated garment. In fact, to avoid the damage aforesaid, means must be provided to automatically stop the thread moving instrumentality the instant that the derangement occurs.

The present invention provides such a means in which the time element is reduced to the smallest component.

The arrangement is such that the instant the thread is broken the safeguarding mechanism operates to effectively stop the fabricating machine before the severed end of the thread or yarn can reach the machine, and it is also so arranged that a knot in the thread, or yarn, cannot pass thru the stop mechanism and into the machine without first stopping the operation of the latter.

Other, further and more specific objects of my invention will become readily apparent, to persons skilled in the art, from a consideration of the following description when taken in conjunction with the drawings, wherein:—

Fig. 1 is an end elevation of the thread guiding device shown in Fig. 2.

Fig. 2 is a side elevation, part in section, of a thread guide for a fabricating machine

in connection with which the stopping mechanism may be used.

Fig. 3 is a section taken on line 3—3 of Fig. 1.

Fig. 4 is a front elevation of the stopping mechanism showing one side wall in section.

Fig. 5 is a section on line 5—5 of Fig. 4.

Fig. 6 is a section on line 6—6 of Fig. 4.

In all the views the same reference characters are employed to indicate similar parts.

The thread guide shown in Fig. 2 comprises a frame 12 having a longer arm 13 and two shorter arms 14 and 15. From the junction 16 of the arms 13 and 15, and 70 rearwardly of the frame arm 13, is a rod 17. Extending vertically from the frame arm 13 is a bearing ear 18 in which is secured a sleeve 19 by a screw 20. This sleeve supports an oscillatable shaft 21, which passes 75 thru it, the free end of which is turned at an angle, as at 22, and again inwardly, to provide a stop 23. On the outer horizontal end of the shaft 21 is supported an arm 24 fixed thereto by a screw 25. Near the lower 80 end of the arm 24 is a laterally extending pin 26, to be engaged by a bifurcated lever 27, which is pivoted, as at 28, to the lower end of the arm 14. Normally the lever 27 rests against a laterally projecting stud 29, which 85 is preferably an integral part of the stationary arm 14. A relatively small elongated shaft 30 is supported on the frame 11. There is fixed to the shaft 30, an arm 31, as by a screw 32, and arm 24 is connected to 90 the arm 31, as by a cord 33. Secured to the shaft 30, at a suitable point is another arm 34, which is connected by a cord 35 to the lever 36 of the stopping mechanism 37.

The mechanism 37 includes a casing 38 in 95 which a vertically reciprocatable rod 39 is normally held under tension, as shown in Fig. 5, by a helical extension spring 40. The rod 39 passes entirely thru the casing 38. The upper end 41 of the spring 40 is secured 100 to the upper wall of the casing by screw 42. The lower end 43 of the spring is secured to the rod, by underlying the head of the screw 44.

The screw 44 passes entirely thru the rod 105 and thru an elongated slot 45, in one of the side walls which is parallel with the movement of the rod 39. A latch lever 45' is pivoted to one side of the rod 39, by screw 50, and on its inturned end is provided with 110

two spaced apart arms 51 and 52 providing a space 53 therebetween to receive the screw 44. The upper end 54 of the latch 45', when released, is caused to pass thru a slot 57 in the side wall 55 of the casing by a light yielding spring 56. The slot 57 is provided in the side wall 55 of the casing 37, thru which the upper end 54 of the latch lever 45' will pass, as shown in dotted lines in Fig. 4, when said lever is released, as at 58.

The rod 39 has been drawn down against the extension spring 40 that surrounds it, and is held in its down position by the screw 44 entering the space 53 between the arms 51 and 52 of the latch lever 45'. When the rod 39 is released, it will move up into the dotted line position, by the operation of the spring 40, as shown in Fig. 5. The rod 39, however, is held by the latch lever 45' and the upper end of the latch lever is retained in its holding position by the bell-crank lever 60, which is pivoted, as at 61, and is provided with a vertically extending arm 36 that passes thru a slot in the upper wall of the casing. The lever 60 is provided with a horizontally projecting arm 62 which is provided with a detent 63 and a stop 64 with an intervening notch 65, so that when the string or cord 35 is pulled, the detent 63 is raised and the upper end 54 of the latch lever 45' is released, thus releasing the rod 39 from its position, confined by the elastic spring 40, whereupon the spring will suddenly move the rod to the dotted line position shown in Fig. 5 and such movement will operate the mechanism required to stop the fabricating machine thru the chain 64. On the lower end of the rod 39 is a chain 64 which communicates with the necessary instrumentalities for stopping the fabricating mechanism.

A spring 66 holds the arm 62 of the lever 60 in depressed position so that it will automatically engage the upper end 54 of the latch member 45', when the rod 39 is drawn downwardly to set the mechanism. The operation of the lever 60 is sensitive and its adjustment with respect to the upper end 54 of the latch lever 45' must be accurate and to this end I provide an adjusting screw 67 having a tapered point 68 and a set nut

69. The tapered point engages the inner edge of the vertical arm 36 of the bell crank lever and determines the engagement of the detent 63 with the upper end 54 of the latch lever.

Now from the foregoing description it will be manifest that when a knot, such as the knot 70, in the cord or string 71, passes between the two parallel spaced apart arms 60 of the pivoted lever 27, that it will move the latter into the position shown in Fig. 2 and said lever will encounter the laterally projecting stud 26, on the lever 24, thereby moving the lever 31 which oscillates a shaft 30 65 and thereby moves the lever 34, and this lever, being connected by a cord 35 with the lever 26 of the bell crank lever, will release the latch lever 45', which will liberate the vertically movable rod 39 and the latter 70 will be quickly and violently moved into a position shown in dotted lines in Fig. 5 by the energy stored in the spring 40.

Having described my invention, what I claim is:—

An organized structure for stopping a fabricating machine upon occurrence of an abnormal condition of a thread, comprising a casing; a rod extending thru opposite walls of the casing for disconnecting said machine from its driving power; an open helical spring, within the casing surrounding the rod and bearing against one wall of the casing to yieldingly hold the rod in position into which it is moved by the spring; a latch lever pivoted at one side of the rod near the bottom of the casing having an elongated end and a short end; a pin extending from one side of the rod passing thru an elongated slot in the casing, to prevent rotation of the rod and to engage the short end of the latch lever to hold the rod depressed against the tension of its operating spring; a spring pressed lever near the upper end of the casing, having one end projecting thru a slot 95 in the casing and another end for engaging the elongated end of the latch lever and means to disengage the aforesaid levers to release the spring and move the rod.

In testimony whereof I hereunto subscribe my name,

JOHN SCHUTZ.
